UNITED STATES PATENT OFFICE.

MAMIE ALICE BAUER, OF LOS ANGELES, CALIFORNIA.

DESIGN FOR AN INCENSE BURNER.

Application filed November 5, 1925. Serial No. 15,357. Term of patent 14 years.

To all whom it may concern:

Be it known that I, MAMIE ALICE BAUER, a citizen of the United States, residing at Los Angeles, in the county of Los Angeles and State of California, have invented a new, original, and ornamental Design for Incense Burner, of which the following is a specification, reference being had to the accompanying drawings, in which—

Fig. 1 is a view as seen in front elevation;

Fig. 2 is a view as seen in side elevation.
I claim:

The ornamental design for an incense burner, substantially as shown.

MAMIE ALICE BAUER.
